UNITED STATES PATENT OFFICE

157,126

POURING VESSEL

Walter L. Bumber, Westmont, Ill.

Application September 9, 1946, Serial No. 133,198

Term of patent 14 years

(Cl. D58—8)

To all whom it may concern:

Be it known that I, Walter L. Bumber, a citizen of the United States and resident of Westmont, in the county of DuPage and State of Illinois, have invented a new, original, and ornamental Design for a Pouring Vessel, of which the following is a specification, reference being had to the accompanying drawing, forming a part thereof.

In the drawing, Fig. 1 is a side elevational view of a pouring vessel, showing my new design;

Figure 2 is an elevational view of the vessel taken at 90° from the view shown in Figure 1;

Figure 3 is a fragmentary sectional view of the pouring spout taken on the line 3—3 of Figure 2; and

Figure 4 is a fragmentary plan view of the pouring spout normal to the bottom of the pouring spout.

I claim:

The ornamental design for a pouring vessel, as shown.

WALTER L. BUMBER.
